UNITED STATES PATENT OFFICE.

WILLIAM WALMSLEY, OF LOWELL, MASSACHUSETTS, ASSIGNOR TO DRAPER COMPANY, OF HOPEDALE, MASSACHUSETTS, A CORPORATION OF MAINE.

BOBBIN-STRIPPER.

1,028,408.

Specification of Letters Patent.

Patented June 4, 1912.

Application filed October 16, 1911. Serial No. 654,970.

To all whom it may concern:

Be it known that I, WILLIAM WALMSLEY, a citizen of the United States, and resident of Lowell, county of Middlesex, State of Massachusetts, have invented an Improvement in Bobbin-Strippers, of which the following description, in connection with the accompanying drawing, is a specification, like characters on the drawing representing like parts.

This invention has for its object the production of a simple and efficient device for stripping the waste yarn from the filling-carriers or bobbins used in the shuttle of a loom, and it is more particularly adapted for use in connection with looms wherein the filling in the working shuttle is replenished automatically. In such looms, and particularly when the replenishment is effected prior to complete exhaustion of the filling in the shuttle, a small portion of yarn remains on the spent bobbin when it is ejected from the shuttle. Before the bobbins can be used over again this waste yarn must be removed, either by knocking or cutting it off by hand, or by some mechanical device.

Heretofore it has been proposed to strip the ejected bobbin as it is discharged from the shuttle, a rotating stripper being arranged to catch the filling-end as the bobbin drops and to wind the waste yarn upon the stripper as it is drawn from the bobbin.

This arrangement, while its operation is in general satisfactory, requires each loom to be equipped with the stripping mechanism. It is customary for one weaver to attend to a group of sixteen or more automatic filling replenishing looms, and the equipment of every loom with a stripping device increases the cost to the mill.

My present invention comprehends a stripping device which in practice will be applied to only one loom of a group, and comprises essentially a rotating stripper mounted on the loom and driven by a moving member thereof, and a holder mounted on the loom adjacent the stripper and adapted to receive and hold temporarily a spent bobbin, with the tip of the latter directed toward the stripper. In practice the holder is made as a series of frictionally acting members each of which is adapted to receive a bobbin. The weaver attending a group of looms takes the spent bobbins from the cans of the various looms and places them on the holders of the

loom equipped with the stripper. The loose ends of yarn from such bobbins are caught by the stripper and wound thereupon as the yarn is drawn off from the bobbin, or bobbins, over the tip end thereof. The stripped bobbins are then removed and placed in a suitable receptacle, ready for further use. As the weaver has to pay no attention to the device, other than to apply and remove bobbins from the holder, he can attend to his other duties as required and at odd moments collects and positions the bobbins to be stripped, and removes the stripped ones. Thus no additional cost for stripping is incurred beyond the equipping of a single loom of each group looked after by a weaver.

The apparatus in itself is very simple, both in construction and arrangement, and performs its designed functions efficiently and substantially automatically.

The various novel features of my invention will be fully described in the subjoined specification and particularly pointed out in the following claim.

Figure 1 is a right hand side elevation, partly broken out, of an automatic filling replenishing loom of the Northrop type with one embodiment of my invention applied thereto; Fig. 2 is a rear elevation of the bobbin stripping device shown in Fig. 1, a portion of the arch of the loom and of the crank shaft and handwheel being shown.

Referring to Fig. 1 the loom frame A, its arch B, the crank-shaft C and the handwheel D thereon, are and may be all of usual and well known construction, and the filling replenishing mechanism comprising essentially the battery E and transerrer F are of the type shown in United States patent to Northrop No. 529,940, dated November 27, 1894.

In accordance with my present invention I apply to the end of the crank-shaft, at the replenishing side of the loom, a stripper, herein shown as a drum comprising circular ends or heads 1 and connecting strips or bars 2 made of wood or other suitable material, the stripper being attached in any suitable manner to the crank-shaft C adjacent the handwheel.

In the preferred form of my invention, as herein illustrated, I mount a bobbin holding device above and adjacent the stripper, and for that purpose an L-shaped bracket 3

is fixedly attached to the loom arch, the long arm of said bracket extending laterally from the arch and above the stripper. This bracket supports a series of bobbin holders 5 of any suitable character such for instance as split spindles 4, see Fig. 2, said holders being fixedly attached to the lateral arm of the bracket and depending therefrom, and preferably the longitudinal axes of these 10 holders are arranged to lie in a plane substantially tangent to the periphery of the stripper. Any other suitable form of bobbin holder may be used provided the bobbin can be readily placed upon or removed 15 from it.

In practice one loom of a group of sixteen or more looms attended by one weaver will be equipped with the stripping device hereinbefore described.

20 The spent bobbins when discharged from the shuttles of the various looms of a group fall into cans or other receptacles provided for the purpose, and ordinarily contain a small amount of waste yarn. The weaver 25 will from time to time remove these bobbins from a can and place them upon the holders 4 as shown in Figs. 1 and 2, each bobbin 5 being held upon its holder with its tip depending and above the stripper. In 30 this position the end of filling 6 hanging down from the waste yarn 7 on the bobbin will be caught by the rotating stripper and wound thereupon, and as the yarn is wound upon the stripper it is drawn off from the 35 bobbin over the depending tip thereof. If the loose ends are short it will be necessary for the weaver to draw off enough yarn from a bobbin to allow the loose end to be caught by the stripper. After a spent bobbin 40 is placed upon a holder and its loose end of yarn is caught by the stripper no further attention from the weaver is required except to remove the bare bobbin whenever convenient, and place it in any 45 suitable receptacle. By equipping one loom in each group with a stripping device such as described, the weaver having charge of that group can place in position to be

stripped bobbins having waste yarn thereon and remove stripped bobbins at odd intervals of time, not interfering in any way with his other duties, the one stripping equipment being sufficient to strip the bobbins from all of the looms of a group. When the stripper becomes overloaded with waste 55 yarn the latter can be cut therefrom and utilized for waste, or for other purposes.

By means of the device herein described no additional cost is incurred for stripping other than the slight cost necessary to equip 60 one loom in each group of looms. The particular construction of the stripper is not material, nor is the particular construction of the bobbin-holding device restricted to that herein shown, for so far as the stripper 65 is concerned any structure may be used which will properly perform the required function and the holder can be of any form which will conveniently hold a bobbin temporarily and in position for stripping.

Having fully described my invention, what I claim as new and desire to secure by Letters Patent is:

In a loom having filling replenishing mechanism at one side of its frame, in combination, a crank-shaft extended beyond the frame at the replenishing side thereof, a drum-like yarn-stripper mounted on such extension, a bracket on the frame adjacent said stripper, and a plurality of split spindles 75 fixedly mounted on and depending from the bracket and pointing toward the stripper, each spindle being adapted to receive and hold temporarily a bobbin with its tip directed toward the stripper, whereby 80 the latter may draw off and wind upon itself the waste yarn from a bobbin held upon a spindle.

In testimony whereof, I have signed my name to this specification, in the presence of 90 two subscribing witnesses.

WILLIAM WALMSLEY.
